UNITED STATES PATENT OFFICE.

EINAR N. RAULAND, OF RIVER FOREST, ILLINOIS, ASSIGNOR TO ALL-AMERICAN RADIO CORPORATION, OF CHICAGO, ILLINOIS, A CORPORATION OF ILLINOIS.

TRANSFORMER.

Application filed March 11, 1926. Serial No. 93,843.

This invention relates to transformers and particularly to an improved casing and construction for audio frequency transformers.

It is the object of the present invention 5 to shield the transformer windings so as to eliminate interaction between adjacent transformers, but without reducing the efficiency of the transformer.

The invention will be best understood by 10 reference to the drawings in which Fig. 1 is a side elevation; Fig. 2 a front elevation; Fig. 3 a vertical cross-section along lines 3—3 of Fig. 1; and Fig. 4 a vertical cross-section along lines 4—4 of Fig. 2.

15 The transformer coil consisting of primary 1^a and secondary 1^b windings is provided on an iron core 2 composed of substantially rectangular laminæ 3. Each lamination is provided with two perforations 20 4 within which the coil is held, and is slit at 5 so that the coil may be slipped in place. The primary 1^a is wound over the secondary winding 1^b in order to reduce the mean turn length of the latter. The distributed capacity is thus reduced to a minimum. The 25 laminations are sheared so that the magnetic leakage and core reluctance may be as small as possible. A heavy gauge of high silicon steel is used whereby maximum iron space 30 is obtained.

The core stands on a platform 6 of sheet metal having a bent-down flange 7. On its two sides the coil is surrounded by two steel shells 8—8 which have suitably bulging portions. The shells 8 are placed on the platform 6 and may be provided with lugs 9 which project through the platform and are bent up to hold the shells in place. A plate 10 is provided against the lower surface of 40 platform 6 within the substantially rectangular space surrounded by flange 7. This plate 10 is so fastened that access to the transformer is prevented. The upper ends and two sides of shells 8 are flattened against 45 the core 2, strips of insulation 11 being provided between the core and the shells. A substantially U-shaped yoke 12 surrounds the iron core 2 on three sides and completes

the transformer casing. The yoke 12 may be provided with lugs like 9 to hold it 50 against the platform 6 or such lugs may be provided only on the yoke, since by means of it shells 8 will be clamped in place. The edges of the yoke are bent down to form flanges 13 clamping the edges of shells 8. 55 Strips of insulation 14 are placed between flange 13 and the edges of shells 8. The terminals of the coil 1 are brought to the outside through perforated binding screws 15 which are mounted on the sides of shells 8 60 and are insulated therefrom by means of discs 16.

By insulating the halves of the steel shell 8, no magnetic circuit will be formed around the coil in a plane perpendicular to its axis. 65 Otherwise, the shell would act as a low resistance turn and decrease the impedance of the primary. Owing to the shape of the shell 8 and the location of the binding posts 15, the lead wires from the coil windings to 70 the posts may be short.

What I claim is:

In an audio frequency transformer, a core composed of substantially rectangular, heavy gauge silicon steel laminæ, a coil surrounding part of said core and surrounded by said core, said coil being composed of a secondary winding surrounded by a primary winding, two steel shells substantially conforming in shape to the core and coil assembly, each 80 shell having an outwardly bulging portion enclosing said coil and flat portions enclosing said core, binding posts mounted on said bulging portion, insulation between contiguous portions of said shells and core, a 85 substantially U-shaped steel yoke surrounding said core on three sides and clamping together said shells, insulation between said yoke and shells, and a base on which the ends of contiguous portions of said core and 90 shells rest, fastened to said yoke.

In testimony whereof, I have signed my name to this specification this 8th day of March, 1926.

EINAR N. RAULAND.
